UNITED STATES PATENT OFFICE

170,837

NECKLACE OR SIMILAR ARTICLE

Raymonde Semensohn, New York, N. Y., assignor to Marcel Boucher et Cie, New York, N. Y., a partnership consisting of Marcel Boucher and Jeanne Boucher

Application July 1, 1953, Serial No. 25,757

Term of patent 3½ years

(Cl. D45—16)

To all whom it may concern:

Be it known I, Raymonde Semensohn, a citizen of the French Republic, residing at New York city, in the county of Kings and State of New York, have invented a new, original, and ornamental Design for a Necklace or Similar Article, of which the following is a specification, reference being had to the accompanying drawing, forming part thereof.

In said drawing,

Fig. 1 is a front elevational view of a necklace, showing my new design.

Fig. 2 is a top plan view of the same.

I claim:
The ornamental design for a necklace or similar article, as shown.

RAYMONDE SEMENSOHN.
